UNITED STATES PATENT OFFICE

LEWIS ELMER HUNT, OF ELK POINT, SOUTH DAKOTA

HEATER DRUM FOR HOG AND POULTRY HOUSES

Application filed October 19, 1929. Serial No. 400,921.

This invention relates to improvements in means for properly caring for the young of live stock during cold weather.

An object of the invention is the provision of apparatus simple in construction and of novel design enabling economical manufacture and ready assembly and installation by the stock raiser without resort to skilled labor.

Another object is the provision of novel means whereby the young stock are warmed by heat produced by radiation from circulating hot air and also are warmed directly by the hot air.

Other objects will appear hereinafter.

The invention consists in the features, combination, and arrangement of parts herein-after described and particularly pointed out in the claims.

In the drawings:

20 Figure 1 is a side elevation.

Fig. 2 is a plan view.

Fig. 3 is a sectional view on line 3-3 of Fig. 2.

Fig. 4 is a sectional plan view with parts 25 broken away showing the connections of the parts of the sectional casing.

Fig. 5 is a plan view of a stock receiving section.

Fig. 6 is a front view of the same.

30 Figs. 7, 8, and 9 are plan, front, and side views respectively of the outer wall portion of a radial wing section.

Figs. 10 and 11 are plan and elevations, respectively, of the top portion of a radial 35 wing section, in which is shown an exit port and cover.

Fig. 12 is a detail of the rear wall of one of the stock receiving chambers C showing the direct communication M between the stock 40 chamber and the stove chamber with the deflector N.

Figs. 13 and 14 are front and side sectional views of another form of structure of the deflector.

45 Figs. 15 and 16 are similar views of a further form.

Figs. 17 and 18 are views of a slidable deflector ash pit door construction shown also 50 in Fig. 3.

Fig. 19 is a view of the metal stove chamber cover in partially open position.

Fig. 20 is a view of another form of the stove chamber cover.

Figs. 21 and 22 are sectional plan and elevational views respectively of a preferred construction employing a horizontal baffle in the radial wings.

Fig. 23 shows the connections of the fences to the radial wings to form pens or yards 60 for the animals, in communication with the stock receiving chambers.

Referring to the drawings by reference characters, the numeral 1 designates a sheet metal casing having a central tubular part 55 1^a of a size adapted to slip over and receive a heating stove such as customarily used, which, being well known, is only conventionally illustrated.

Extending radially outward from the cylindrical portion 1^a are a plurality of radial hollow partition and radiator members or wings 1^b, the hollow interiors B of which communicate with the stove chamber A and receive heated air therefrom.

70 The tubular portion 1^a of the casing forming the stove chamber A may be of any desired shape such as cylindrical and may include arc shaped wall sections, but preferably, and as shown, the tubular portion 1^a 75 is polygonal in shape and includes flat wall sections 1^c alternating with open spaces 1^d which communicate with the radial partition members or wings 1^b.

The radial partition members or wings 80 flare outwardly at their outer ends and form between them and the central tubular portion 1^a, stock enclosing chambers C which have restricted entrances thereto as indicated at d which are intended to be of such size that 85 the young of the stock (for example small pigs) can find entrance to the stock chambers C while the full grown animals will be excluded therefrom.

90 Preferably, the casing is formed by readily attachable and detachable sections simple in design and few in number. A plurality of stock chamber sections F are provided, each comprising a piece of sheet metal bent to 95 form the back wall portion F¹, which also 100

forms the wall of the stove chamber A, and the adjoining flaring side wall portions F² (Figs. 5 and 6). The stock chamber sections F are readily and detachably connected by stove bolts G or the like to radial wing detachable sheet metal sections H (Figs. 7 to 11), comprising the outer wall portion H¹ and top portion H². The sections F and H each are provided with bottom or base flanges J to enable them to be secured to the floor. The outer wall portion H¹ of the radial wing preferably constitutes a section separate from the top portion H² and secured thereto by stove bolts G.

15 The connection between the sections F and H is established by providing an upstanding edge flange on the top section H² and connecting this flange to the overlapping top edge of the section F by means of the stove bolts 20 passing therethrough, as shown in Fig. 3. This upstanding flange on the top section H² serves also to removably connect it with the top of the outer wall section H¹ of the radial wing H in a similar manner by stove bolts 25 G or the like.

The front edges of sections F join the side edges of the outer wall portions H¹ by overlapping as shown in Fig. 4 and being secured by stove bolts.

30 In the embodiment shown, there are five stock chamber sections F and five radial wing sections H (including top and outer wall sections H² and H¹), which together make up the entire brooder casing, the radial wings 35 being open from top to bottom at their inner ends where they communicate with the stove chamber A. It will be understood that the number of radial wings may be varied by increasing or decreasing without departing 40 from the scope of the invention. Five wings provide a desirable arrangement, although a practical embodiment may be produced having only three wings.

Tie rods or braces K are preferably provided connecting the top of each radial wing 45 with the adjoining one in order to give the brooder strength.

In the central outer wall of each section H¹ and adjacent the bottom thereof are provided one or more cold air inlet apertures L, preferably two as shown. Further holes may if desired be provided in the angularly adjoining outer wall portions, but are preferably confined to the central outer wall, as 55 shown.

The air enters through these apertures L and passes through the radial wing into the stove chamber and is heated by the stove from which chamber it may recirculate into the 60 radial wings again and heat side walls of the wings which are the side walls of the stock chambers and thus heat the chambers by radiation.

The inner wall F¹ of each stock chamber 65 section F is preferably provided according

to the invention with an opening M providing direct communication between the stove chamber A and the stock chambers C. A portion of the air entering through the ports L and heated by the stove, passes directly 70 from the stove chamber A to the stock chambers through the opening M. The opening M is preferably located at a point nearer to the bottom of the wall F¹ than to its top, so that the young stock will receive the full 75 benefit of the heated air, which of course rises after being delivered to the stock chamber.

A fixed or hinged deflector N is disposed 80 above the opening M and serves to deflect the hot air in a downward direction toward the bottom of the stock chamber. This opening M permits the warm air to pass directly 85 into the stock chamber from the heated central chamber and does not interfere with the circulation of the hot air through the several radial wings. The deflector N and opening M may be formed by merely cutting a half circle or more in the sheet metal of the wall F¹ and bending it out. This forms a permanent opening with a fixed deflector as 90 shown in Figs. 3, 4, 5, 6, and 12. The fixed deflector may also be provided by securing a separate piece of sheet metal N¹ at the top of the hole M¹ by means of rivets or bolts O as shown in Figs. 13 and 14. A further way of mounting the deflector is shown in Figs. 15 and 16, in which the deflector N² is hinged 95 above the opening M² as shown at P and is held open by a wire or chain R having an end 100 hooked over the top edge of wall F¹. By this arrangement, the direct communication from the heating chamber to the stock chambers may be closed if and as desired.

Referring to Fig. 3, the arrows show the 105 cold air entering the radial wing through the openings L and passing through the lower part of the radial wing and circulating through the heating chamber A and around the heating unit or stove. Some of the hot 110 air passes back through the upper portion of the radial wing and heats the walls thereof being the walls of the stock enclosing chambers and some of the hot air passes directly 115 through the openings M into the stock chamber. This takes place in each radial wing and in each stock chamber as will be apparent. The arrows show the circulation of the air in a general way.

Each radial wing may be provided, if desired, with an opening in the upper or top surface thereof as shown at S, which is provided with a closure member S¹, and through which when opened more or less by regulation of the closure member, hot air may escape into the building in which the brooder is housed. This may be desired to enhance circulation or to provide heat to the room in which the brooder is housed, in addition to that passing out of the stock chambers.

The central chamber A is provided with a top closure indicated at *a* which is of general annular or ring form having a central opening *e* for the passage of a smoke pipe from the stove. The top closure member *a* is of a size to overlie and be supported by the top of the tubular portion *1^a* of the brooder as shown at *b*.

The closure member *a* comprises a flat circular sheet of metal formed in two parts by being split diametrically and is hinged at *f* to be swung open when it is desired to refuel the stove. The two halves preferably overlap slightly and the hinge *f* is formed by simply passing a bolt through the two halves at one end of the split. At the other end of the split, holes *g* may be provided in the overlapping section adapted to be aligned and to be held together by a suitable pin *h* passed through the holes, as shown in Fig. 3.

Fig. 19 shows the sheet metal cover *a* opened a short distance through its diameter. When the cover *a* is opened, fuel may be fed into the stove through the fuel feed door in the stove which is so disposed in the upper part of the stove as conventionally shown that it can be provided with fuel directly into the fire-box through the top of the heated chamber A. It will be apparent that for this purpose the split cover disc *a* may be opened fully so that the entire central portion of the heated chamber is uncovered, and may be closed to completely cover the said central portion of heated chamber A.

An oil burner may be used in place of the coal stove in which case the cover *a'* as shown in Fig. 20 will be provided with an opening *k* for the vent or smoke pipe of the burner and an opening *k'* for supplying oil to the burner.

The back vertical wall portion *F¹* of the stock receiving section adjacent the ash pit of the stove, where a coal stove is used, is provided near its lower end with an opening *M³* adjacent the ash pit for ash removal. Referring to Figs. 3, 17, and 18, this opening *M³* has a closure member or door *T*. The door *T* is slidably mounted for vertical sliding movement with respect to the opening *M³* to open or close the same. On either side of the opening guide plates *T¹* are secured to provide guide grooves *T²* between them and the wall bounding the opening, for slidably receiving the door *T*. The door *T* is bent outward at its lower end to provide a deflector *T³* so that when it is opened, the hot air will pass and be deflected into this stock chamber as it does into the others. Normally, the door *T* is not completely closed, but is left open or raised partially so that the hot air may pass into the stock chamber, although it may be closed entirely if desired. In removing ashes, the door may be raised to provide adequate opening for this purpose. The door *T* proper is wider than the deflector *T³* so that the sides

can slip behind the plates and slide into the slots or grooves *T²*, and the deflector can move up and down between the guide plates *T¹* as the door is moved. The ashes are readily removed by an attendant who gets into the stock compartments, the compartments being intended to be large enough to accomplish this.

Fences *U* forming radial continuations of the radial wings are centrally joined thereto as shown in Fig. 23 and together with a generally circular or peripheral surrounding fence *V* form separate pens or yards *W*, with which the stock compartments communicate through openings *d*, as shown.

The whole device including the heater, the brooder casing with its radial wings and stock chambers, and the pens or yards may be enclosed in a shelter house which as it forms no part of the present invention, is not shown herein. It will be apparent that instead of the surrounding fence *V*, the walls of the enclosing building may serve the same purpose.

As shown particularly in Figs. 21 and 22 a horizontal baffle plate *X* is preferably mounted in each radial wing under which it is intended that the cold or unheated air shall pass through the lower part of the radial wing in entering heated chamber A, and over which the heated air may re-circulate in the upper part of the radial wing. The baffle plate is not restrictive in this connection, since it terminates short of the outer end of the radial wing as shown at *Y* which of course permits commingling of the cold and heated air. The purpose of the baffle is to tend to direct in a general way the unheated air into contact with the heater and then in part back into the radial wing to heat the stock chamber walls. The baffle as shown is loosely supported near one end upon a rod *X¹* across the opening *1^a* and near the opposite end upon pins or bolts *X²*. The baffle or partition *X* is disposed nearer to the bottom of the radial wing than to its top.

This application is a continuation in part of that filed by me May 29, 1928, Ser. No. 281,457, for heater drum.

I claim:

1. Apparatus for the purpose described comprising a hollow sheet metal casing forming a stove enclosing chamber, said casing having hollow vertical radially disposed wing portions communicating with the stove chamber and forming therebetween heated compartments for admission of stock, said radial wing portions having openings therein in the lower portion of their outer ends for the admission of air to be heated and circulated through the casing and radial wings to heat the said compartments.

2. Apparatus for the purpose described comprising a hollow sheet metal casing forming a stove enclosing chamber, said casing

- having hollow radially disposed wing portions communicating with the stove chamber and forming therebetween heated compartments for admission of stock, said casing having air inlet openings therein admitting unheated air to circulate through said stove chamber and through said hollow radial wings to heat the walls thereof, which are also the walls of the stock compartments, thereby heating said compartments by radiation from the walls, said casing having hot air outlet openings therein admitting hot air directly from the stove chamber to the stock compartments.
3. Apparatus according to claim 2 in which the closed tops of the radial wing portions are provided with exit ports for heated air, which ports are provided with closure members.
4. Apparatus for the purpose described comprising a hollow sheet metal casing forming a stove enclosing chamber, said casing having hollow vertical radially arranged wings communicating with the stove chamber and forming therebetween heated compartments for admission of stock, in which the closed tops of the radial portions are provided with exit ports for heated air which ports are provided with closure members.
5. Apparatus according to claim 2 in which said air inlet openings are disposed near the bottom of the front wall of the radial wing portions, said casing having angularly disposed deflectors disposed at the hot air outlet openings to direct the hot air downwardly into the stock compartments.
6. Apparatus according to claim 2 including means for closing said hot air outlet openings, said closing means including a movably mounted deflector member adapted when open to direct the hot air downwardly into the stock compartment.
7. Apparatus according to claim 2 in which said casing is composed of a plurality of sections removably secured together, said sections including radial wing sections composed of outer wall and top, and compartment or stock receiving sections alternately secured to said wing sections and composed of rear inner stove chamber wall and adjoining substantially radially extending walls, and means for removably securing the top to the front wall of the wing sections and for securing the wing sections to the compartment sections.
8. Apparatus according to claim 2 in which said stove chamber of the casing is open at the top and a cover member for said stove chamber comprising a transversely split plate hinged at one end and adapted to rest at its marginal portions upon the casing and to be swung open to provide for feeding fuel to the stove, said cover having an open-
- ing therein to provide when closed for passage of a pipe from the stove.
9. Apparatus according to claim 2 in which the wing portions are in open communication at their inner ends with the stove chamber from top to bottom, and in which the inner walls of said compartments form the walls of the stove chamber and are alternately spaced apart by said openings, said inner walls of the compartments having openings therein establishing direct hot air outlets from the stove chamber to the compartments, one of said hot air outlets serving also as an ash removal opening, and being provided with a vertically slidable closure member having a deflector.
10. Apparatus according to claim 1 in which said radial wing portions are provided with a horizontally disposed baffle plate separating the wing portion into upper and lower chambers and serving to direct the unheated air from the said inlet openings through the lower chamber into the central stove chamber, and to direct heated air from said central stove chamber into the upper chamber of said wing portion.
- In testimony whereof, I affix my signature.
- LEWIS ELMER HUNT.
